UNITED STATES PATENT OFFICE.

ADOLF THORVALD MOE, OF CHRISTIANIA, NORWAY.

CALCULATING MACHINE.

Application filed April 25, 1923. Serial No. 634,584.

To all whom it may concern:

Be it known that I, ADOLF THORVALD MOE, mechanician, citizen of Norway, residing at Torvet 9, Christiania, Norway, have invented 5 certain new and useful Improvements in Calculating Machines, of which the following is a specification.

The present invention relates to calculating machines and it consists of the novel 10 construction, combination and arrangement of parts hereinafter shown, described and claimed.

The main object of this invention is to produce a calculating machine, which is simple 15 and concentrated, so that it is cheap to manufacture and does not occupy much space.

Other objects of the invention will appear from the following detailed description, reference being made to the accompanying drawings, in which—

Fig. 1 shows a longitudinal section through a portion of the machine.

Fig. 2 is a corresponding plan view of the 25 machine, the top plate of the case having been removed.

Fig. 3 shows a longitudinal section through the key mechanism of the machine.

Fig. 4 shows a section taken on the line 30 IIII—IIII in Fig. 3, the section being seen from left in Fig. 3.

Fig. 5 shows a vertical longitudinal section through the actuating mechanism of the addition wheel and the mechanism controlling the carrying, and

Fig. 6 is a corresponding plan view, partly shown in section.

The invention relates to the type of calculating machines in which the numbers are 40 set in the addition mechanism by depression of keys, which through suitable abutments limit the rearward movement (which means in the direction away from the operator) of a rod or rail to a distance depending upon 45 the value of the depressed key, whereby the actuating mechanism of the addition wheels is so set, that each wheel is turned forward the steps desired, when the rod or bar is moved back to its normal position.

According to the present invention each of 50 said rods or bars are provided with such abutments for cooperation with the abutments of the keys, that each key may be given exactly the same shape, whereas in known machines of the type referred to, each of the

keys has a shape different from those of the other keys in the same series of keys.

The key mechanism and the stop and release arrangements therefore will now be described in detail.

Each additional wheel 1 is turned by means of a rack 2 formed in a bar 3. The bars 3 are slidably mounted in corresponding slots formed in walls or partitions 4 and 5 respectively, which depend from the case 60 of the machine. The bars 3 extend adjacent to the corresponding series of keys.

Each bar 3 is at the upper edge thereof provided with eight grooves 6, each of which cooperate with a nose 7 arranged upon each 70 of the keys 8, which are situated adjacent to the bar. The length of each of said grooves is so chosen, that when a certain key is depressed and the operating handle turned, the bar 3 is allowed to slide such distance that 75 the actuating mechanism of the addition wheels is thereby imparted the movement necessary to turn the addition wheels the number of the steps determined by the key depressed, the movement of the bar being 80 limited by the rearmost edge 6' of the groove 6 abutting against the nose 7 of the key. The bar 3 has no groove corresponding to the key allotted for the figure nine, this key 85 not being provided with a nose. However, this key, when depressed, releases the bar 3, whereupon the movement of said bar is limited by an abutment which will be described below. At that side of each row of the keys 8, which is opposite to the bar 3, is arranged 90

a bar 9 provided at each end thereof with a lug 10 by means of which the bar is pivotally mounted in the partitions 4 and 5 respectively. By means of springs 11 which pass from the upper edge of one bar 9 to 95 the lower edge of the adjacent bar 9, the lower edge of the bars are tilted in against the shaft of the keys, the bars thereby being held in an inclined position. Each key-shaft is provided with a stop-nose or projection 100 12 and also with a projecting portion 13. When a key has been depressed the lower edge of the bar 9 rests upon the stop-nose 12 and the portion 13 causes the bar 9 to occupy a somewhat more vertical position, as 105 shown at the depressed key in Fig. 4. Each bar 9 carries a curved arm 14 which in normal position of the bars project into a groove 15 in the corresponding bar 3, thereby locking the latter one. However, when a key is 110

- 2
- depressed (see Fig. 4) the stop-nose 12 thereof will cause the bar 9 to move into such position that the arm 14 is swung out of the groove 15 whereby the bar 3 is released.
- 5 Then the bar 3 may be moved until the nose 7 of the depressed key abuts against the rearmost edge of the corresponding groove 6. The lower portion of each key 8 is guided in holes in a plate 16, which is arranged between the partitions 4 and 5, and the depressed keys are moved back to normal position by means of springs 17, which are situated between said plate 16 and suitable shoulders upon the key-shaft.
- 10 When a bar 3 slides as mentioned above, the rack 2 acts upon a toothed wheel 18, which is loosely mounted upon the shaft 19 of the addition wheels 1. To the wheel 18 is rigidly connected an arm 20, which carries a pivotally mounted actuating-pawl 21. A spring 22 keeps the pawl 21 in mesh with pins 23, which in the usual way are arranged upon the loosely mounted addition wheel 1. (In the example here shown the number 25 of pins 23 is twenty). Upon the wheel 1 are arranged, in diametrically opposite positions, two pins 24, which act upon the carrying mechanism, that will be described later.
- 20 At the lower side of each addition wheel a retaining pawl 25 acts from outward against the pins 23. This pawl is pivotally mounted upon a transverse shaft 26 and is kept in mesh with the pins 23 by means of a spring 27.
- 30 The movement of the bars 3 to the right (Fig. 1) is effected by means of an actuating arm 28, one arm being provided for each bar. Said actuating arms may consist of a spring-like formed metal rod, which is wound around an actuating shaft 29 in the case in such manner that the arm proper 28, forms the one end of a screw spring. On the shaft 29 is also loosely mounted a frame consisting of one transverse portion 30 and two end portions 31, which frame serves to retain the arms 28 which rest against the transverse portion 30, the other end 32 of the screw spring, projecting upwards at the other side of the shaft and being secured to the portion 30 by means of a screw 33. When the frame 30, 31 is tilted on the shaft 29, the upper end of the arm 28 acts against a pin 34 upon each bar 3, whereby the bars are moved forward or towards right in Fig.
- 40
- 45
- 50
- 55
- 60
- 65
3. Usually all bars are not moved the same distance, because they are locked in different positions. When a certain bar 3 is locked, and the frame 30, 31 continues its movement, the arm 28 is bent to the left, against the spring action thereof, and leaves the transverse portion 30. The strength of the spring action of the arm 28 and accordingly the strength of its action upon the bars 3 may be regulated by adjustment of the screw 33.

When a key allotted to the figure nine is depressed, it only releases the corresponding bar 3, because the key is not provided with means for limiting the sliding of the bar towards the front. The limiting means which act in this case, is the pin 34, the distance between the front side of said pin and the partition 4 being so chosen that the movement of the bar 3 corresponds to the movement of the actuating pawl 21 over nine of the addition wheel pins 23.

The arms 28 are actuated by the following arrangement: To one of the end portions 31 is secured a vertically extending operating arm 35, which near the top thereof by means of a pivot 36 carries a pivotally mounted lever 37, the other end of which pivots on a pin 38 that is secured to the operating-handle 39 of the machine. The handle 39 is mounted upon a shaft 40, journalled in the case. The end positions of the handle 39 are determined by pins 41, covered with a sleeve 42 of rubber or similar material, to prevent noise. To the pins 41 is also secured a plate 43, which at its lower edge carries a curved bar 44. The curvature of the bar corresponds to a circle, whose centre lies in the axis of the shaft 40, and the bar is provided with small teeth 44, which cooperate with a reversible pawl 46, that is pivotally mounted upon a lug 45 on the handle 39, and is normally kept in its middle position by means of a spring 47. The pawl 46 coacts with the teeth 44 of the bar during the operation of the handle 39 in either direction, in such manner that when the movement of the handle 39 is once begun, it can not be returned to the original position until it is first moved over the entire length of the bar, to the other end position.

On the pin 38 of the handle 39 is also pivotally mounted a lever 48, the other end of which passes through a slot 49 in the partition 5. On that portion of the lever 48 which passes through the partition 5, is formed an oblique surface 50, which is so arranged that at the moment the handle 39 and accordingly also the lever 48 moves to the right, the surface 50—which in the position of the lever 48 shown in Fig. 3 rests against the bottom of the slot 49—will slide downwards thereby lowering the outer end of the lever 48. This causes a nose 51 on the lever 48 to be lowered into mesh with a projecting portion 52 of an angle-lever 53, which by means of a screw 54 is pivotally mounted on the case. The other arm of the lever 53 co-operates with the oblique end surface 55 of a releasing bar 58, which by means of screws 56 passing through slots 57 in the bar, is slidably mounted on the partition 5. The bar 58 is provided with a series of grooves 59, into each of which projects the lower edge of the corresponding

lock bars 9 of the keys 8. When the handle 39 is moved back to its original position (shown in Fig. 3), the nose 51 acts against the projection of the lever 53, thereby turning the latter. This causes one of the arms of the lever 53 to slide upwards along the oblique end surface 55 of the releasing-bar 58, whereby the bar is moved to the right (Fig. 4) and the side walls of the grooves 15 in the bar 13, which takes up the locking arm 14, being made so broad that the necessary movement of the bar 3 is allowed during the carrying operation.

5 turn the bars 9 against the action of the springs 11, thus unlocking the keys 8, which are then pressed upwards and into normal rest-position by the springs 17. When the nose 51 has turned the lever 53 so far that 10 the keys are unlocked, the inclined surface 50 of the releasing-bar 58 reaches the bottom of the slot 49, and during the continued movement of the handle towards left, the lever 48 is thus again raised, whereby the 15 nose 51 is moved out of mesh with the projection 52 and the lever 53 is released. A spring 60 then moves the lever 53 to normal position, and at the same time the lock-bar 9, through the action of the springs 11, 20 moves the bar 58 towards left (Fig. 4) into its original position.

The carrying mechanism used in the present calculating machine is previously known as to its proper principle, but the several 30 parts thereof are constructed and arranged in a new and very simple and efficient manner, as will be seen from the following.

On the shaft 26, which carries the retaining pawls 25, is also pivotally mounted a plate 61, which is provided with a knee-shaped finger 62, that rests against the foremost side 63 of a groove 64 in a reinforcing partition 65, which is arranged between adjacent addition wheels, whereby the plate 61 is kept at a certain distance from the wheel 1. At a distance from the top thereof, the plate 61 is provided with a seat 66 adapted to cooperate with a projecting nose on the actuating pawl 21. When the pawl 21 occupies 45 the position shown in Fig. 5, its position will be considered normal. When an addition wheel 1 turns from that position in which the figure "9" is seen in the opening 68 (Fig. 1) and into the next position in 50 which the figure "0" is seen in the said opening, the pin 24 on said addition wheel will meet and slide upon the inner bevelled end surface 69 of the finger 62 of the addition wheel of next higher order, thereby pressing said finger backwards. This releases the 55 pawl-nose 67 from the seat 66, and allows the pawl-nose 67, together with the wheel 1 to turn one step forward until the pawl-nose meets a shaft 70, which passes through 60 the partitions 65 and serves as an abutment for the pawl-nose 67. The mentioned extra-step movement of the wheel 1 and the pawl-nose 67 (the carrying movement) is caused by a spring 71, which serves to bring the 65 bar 3 back to original position, the groove

15 in the bar 13, which takes up the locking arm 14, being made so broad that the necessary movement of the bar 3 is allowed during the carrying operation.

If the pawl 21 is still continuing its normal actuating movement and thus has not yet reached the normal rest position (shown in Fig. 5), in the moment when the carrying pin 24 releases the seat 66 from the nose 67, the arm 61 is, during its backward movement, locked in a groove 72, which is arranged in a lever 74 that pivots on a shaft 73. The rear end of said lever 74 is connected to the lower end of the arm 61 by means of a spring 75, which on the one side 70 presses the lever 74 against the lower side of the knee-lever 62 and on the other side 75 presses the arm 61 against the side wall of the groove 64. During the last part of the carrying movement of the pawl 21 and just 80 before the pawl abuts against the shaft 70, a finger 76, which is connected to the toothed wheel 18, will abut against the inner end of the lever 74 and press the same down, whereby the arm 61 carrying the seat 66 is again 85 released and tilts into normal position, resting against the side wall 63 of the groove 64.

It is thus seen, that during or after an addition, some of the pawls 21 may be in 90 position of rest, whereas others may be turned one extra step forward, thus resting against the shaft 70. Now, in order that the carrying mechanism described above shall 95 be able to carry at the following depression of a key 8, all of the last named pawls must be brought back to the position shown in Fig. 5, because the pawls 21 only are able to carry from this position. This return of the pawls 21 is effected during the first 100 part of the rearward movement of the bar 3, the play between the foremost side wall of the groove 15 and the rear edge of the arm 14 being then eliminated. As to those bars 3, whose actuating pawls 21 have not 105 carried during the last addition, no movement of said bars will occur, the play space between edge of the arm 14 and the edge of the groove 15 being situated at the right side of the arm 14 (Fig. 3), and no play 110 space will exist at the left side of the arm 14 to allow for the forward movement of the bar 3.

The zero-setting of the addition wheels 115 is effected by means of the following arrangement:

On the shaft 77 is pivotally mounted a U-shaped member 78, whose transverse portion extends below the rear part of the retaining pawls 25. To one of the branches 120 of said member 78 is secured a lever 80, the end of which extends through and is vertically guided by a slot 79 in the partition 5. Connected to the lever 80 is a key 81, which also carries a stop finger 82 for the bar 3 125 of the addition wheel of the highest order, 130

no key-series being arranged for said addition wheel.

When the key 81 is depressed, the lever 80 slides along an inclined surface 83 of a groove, which is arranged in the transverse bar 58. This causes the bar 58 to move to the right (Fig. 4) whereby all lock-bars 9 are tilted and move their corresponding arms 14 out of the grooves 15 in the bars 3, where-
 10 by the latter ones are released. At the same time the transverse portion of the U-shaped member 78 is raised to abut against the retaining pawls 25 and moves the same out of mesh with the pins 23. When the operating handle is now turned forward and then backward again, all of the bars 3 move, and carry with them their corresponding actuating pawls 21, which latter by friction move their corresponding addition wheels 1, until
 15 the carrying pawls 24 of the wheels 1 abut against the lower edge of the knee-shaped finger 62. The addition wheels then are zero-set, the figure "0" appearing in all of the apertures 68 of the case.
 20 25 When the bars 3 are at rest, a certain play must exist between the actuating arms 28 and the pins 34, to allow for the forward movement of the bars 3 during the carrying movement, and for this reason the springs

- It is seen, thus, that the depressed and locked keys are as usual automatically released as soon as the addition is completed. If, however, the angular lever 90, that is mounted upon the partition 5 is tilted forward, the nose or projection 91 of the lower part of said arm is moved below the arm 48, and the said automatic release of the keys can not take place, because the outer end of the arm 48 can not then be lowered so far that the nose 51 meets the projection of the angular arm 53. The bar 58 is accordingly not acted upon, when the handle 39 is returned, and the sum represented by the depressed keys may be introduced in the addition mechanism repeatedly, by turning the handle 39 the desired number of times. The arm 90 is, therefore, used when multiplications are to be carried out.
- If a key has been erroneously depressed, this is remedied by depression of the correct key, because, when the second and correct key of the series is depressed, the bar 9 thereof is turned out of mesh with the stop nose 12 of the key first depressed whereby the latter is released and moved to original position, whereas the correct key is locked in depressed position.
- If an incorrect series of keys has been used, the error may be corrected by depression of the release-key 81, which acts upon the bar 58 to release all the series of keys, whereupon the correct keys may be depressed.
- Having now particularly described and ascertained the nature of my said invention, and in what manner the same is to be performed, I declare that what I claim is:
1. In a calculating machine, addition wheels, pins carried by said wheels, movable bars having teeth formed therein, toothed wheels meshing with the toothed portion of the bars, an actuating pawl carried by each toothed wheel, means normally retaining the actuating pawl in engagement with the pins of the addition wheels, a movable part, a seat on said movable part, a shaft pivotally mounting the movable part, each pawl being maintained in its rest position by said seat.
  2. A calculating machine as claimed in claim 1, characterized by the provision of retaining pawls mounted on the shaft and associated with the addition wheels.
  3. In a calculating machine, addition wheels, actuating means for the addition wheels, bars associated with and adapted to set the actuating means, a series of keys associated with each bar, each bar having a groove for each key of the series associated therewith, and a nose on each key adapted, when the latter is depressed to co-act with the edges of the groove associated therewith to limit the movement of the bar, the length of said grooves being so chosen that the bar may move the actuating mechanism a distance corresponding with the value of the depressed key, actuating means for the bars consisting of a shaft, a frame mounted on said shaft, and resilient actuating arms coacting with the bars having portions thereof coiled around the shaft, and means for varying the tension of the resilient arms.
  4. A calculating machine as claimed in claim 3 characterized in that the releasing bar is provided with grooves receiving the lower edges of the rotatable locking bars and permitting key locking movement of the latter.
  5. A calculating machine as claimed in claim 3 characterized in that the arm is provided with a groove having inclined portions cooperating with an abutment whereby said arm is caused to lower during its rearward movement whereby to engage and operate the angular lever whereby during its opposite movement said arm is raised.
  6. A calculating machine as claimed in claim 3, characterized by the provision of a pivoted lever, and means on said lever adapted to engage and maintain the arm in inoperative position whereby to prevent co-operation of the latter with the angular levers.
  7. In a calculating machine, addition wheels, actuating means for the addition wheels, bars associated with and adapted to set the actuating means, a series of keys associated with each bar, each bar having a groove for each key of the series associated therewith, a nose on each key adapted, when the latter is depressed to co-act with the edges of the groove associated therewith to limit the movement of the bar, the length of said grooves being so chosen that the bar may move the actuating mechanism a distance corresponding with the value of the depressed key, actuating means for the bars consisting of a shaft, a frame mounted on said shaft, and resilient actuating arms coacting with the bars having portions thereof coiled around the shaft, and means for varying the tension of the resilient arms.
  8. In a calculating machine, addition

wheels, actuating means for the addition wheels, bars associated with and adapted to set the actuating means, a series of keys associated with each bar, each bar having a groove for each key of the series associated therewith, a nose on each key adapted, when the latter is depressed to co-act with the edges of the groove associated therewith to limit the movement of the bar, the length of 10 said grooves being so chosen that the bar may move the actuating mechanism a distance corresponding with the value of the depressed key, a shaft, a frame mounted on said shaft, resilient actuating arms for the 15 bars actuated by said frame, an arm carried

by said frame, an operating handle, means connecting said handle with said arm, bevelled surfaces on said arm, a spring actuated roller co-acting with said bevelled surface during movement of the operating handle in a forward direction to ease the springs acting during movement of the operating handle in the opposite direction upon the other bevelled surface to move the operating arm and the operating handle to a position 20 of rest, the back-moving spring not acting upon the actuating arms during the last part of said movement.

In testimony whereof I affix my signature.

ADOLF THORVALD MOE.
